UNITED STATES PATENT OFFICE.

WILLIAM WATSON CAMP, OF STRATFORD, ONTARIO, CANADA.

BAG-HOLDER.

1,216,941.

Specification of Letters Patent. Patented Feb. 20, 1917.

Application filed November 1, 1916. Serial No. 128,965.

To all whom it may concern:

Be it known that I, WILLIAM WATSON CAMP, of the city of Stratford, in the county of Perth, in the Province of Ontario, Canada, have invented certain new and useful Improvements in Bag-Holders, of which the following is the specification.

My invention relates to improvements in bag holders and the object of the invention 10 is to devise a simple form of bag holder which may be used either on even or uneven ground, in which the bag mouth stretcher may be readily removed from the major portion of the holder for the purpose of 15 shaking the bag, in which the front portion of the mouth of the bag is depressed so as to allow of the easy pouring in of the grain, in which slack in the mouths of larger sized bags than are ordinarily used 20 may be taken up so that the mouth of the bag will fit the holder and in which the base of the holder may be utilized for a truck for transporting the bag when filled from place to place and it consists essentially of the 25 following arrangement and construction of parts as hereinafter more particularly explained by the following specification.

Figure 1, is a general perspective view of my bag holder showing the bag in position.

30 Fig. 2, is a vertical section through Fig. 1.

Fig. 3, is a sectional detail showing the base of the bag holder and bag holder proper detached so that it may be hung upon a suitable support.

35 Fig. 4, is a perspective detail of the bag holder standard.

Fig. 5, is a perspective detail of the bag mouth stretcher showing the bag in dotted lines.

40 Fig. 6, is an enlarged sectional elevation of the supporting bracket for carrying the spring finger for stretching the bag mouth.

Fig. 7, is a perspective detail of the means for taking up the slack of a larger sized 45 bag.

In the drawings like letters of reference indicate corresponding parts in each figure.

1 indicates the base of the holder which is in the form of a truck and comprises longitudinal bars 2 and 3, a cross piece 4 connecting the bars 2 and 3 together at the rear end of the truck, a cross bar 5 connecting the bars 2 and 3 together at the front end of

the truck, and an axle 6 preferably being countersunk on the cross piece 4 and provided with carrying wheels 7 and 8. 9 indicates the usual foot piece carried at the rear end of the longitudinal bars 2 and 3. 10 indicates a U-bracket secured to the normally lower face of the bar 5. 11 indicates an orifice formed in the forward edge of the cross piece 4. 12 indicates a bar standard which is slipped through the bracket 10 and into the orifice 11 at its lower end. 13 and 14 indicate diametrically opposite perforations extending through the walls of the orifice 11. 15 indicates a split pin which extends through the perforations 13 and 14 and through the perforation 16 formed in the standard 12 in proximity to its lower end. The upper end of the standard 12 is hook-shape at 17 as indicated in the drawings. 18 indicates a cross piece provided with a central orifice 19 through which the standard 12 extends. 20 indicates a set screw extending through the cross piece 18 against the standard 12 to secure it in place in any desired position upon the standard 12.

I will now describe the means for holding 80 the bag stretcher in the open position.

21 and 22 indicate a pair of hook members each having rearwardly hooked upper ends 23 and forwardly hooked lower ends 24. 25 indicates a bar which is secured to 85 the inner face of the upwardly extending portions of the back portions 24. The ends 26 and 27 of the bar 25 are inclined in an outward direction and extend at a slightly downward incline. 28 indicates a bracket 90 secured to the arm 27. The lower end of the bracket is provided with an out-turned portion 29, the outer end of which is curved downwardly into U-form at 30 thereby forming two horizontal arms 29^x and 30^x. 95 31 indicates a spring finger provided in proximity to one end with a spring coil 32 and a down-turned portion 33 passing through the alined orifices 34 and 35 formed in the arms 29^x and 30^x thereby forming a 100 vertical bearing for the arm 31. The opposite end of the arm 31 is provided with an inturned portion 36 terminating in a down-turned portion 37 designed to enter the mouth of the bag at the center of the front. 105 38 indicates a supplemental bracket pro-

vided with an inverted U-shape double portion 39 designed to fit over and grip the side portion 26 or 27 of the bar 25. The lower end of the depending portion of the bracket 38 is provided with an out-turned portion 39 provided with an orifice 40. 41 indicates a pin extending upwardly through the orifice 40 and split longitudinally from its upper end. The opposite or lower end 10 is provided with a flattened head 43. 44 indicates a washer which is secured upon the pin 41 so as to bear against the lower face of the portion 49 of the bracket 38. 45 indicates a ratchet wheel also secured upon the 15 pin 41 and bearing against the upper face of the portion 39. 46 indicates a spring dog pivotally mounted upon the portion 49 and co-acting with the ratchet 45.

Having described the principal parts involved in my invention I will briefly describe the operation of the same.

Under ordinary circumstances when a flat draw is provided the truck is set up vertically in the position shown in Fig. 1 so as to be supported upon the wheels 7 and 8 and foot 9. In this position the standard 12 extends vertically, the hook portions 23 of the brackets 21 and 22 being fitted over the arms of the cross piece 18. When in this position the mouth of the bag is inserted between the outwardly extending arms 26 and 27 of the bar 25 and the edge of the bag folded over the upper edge of this bar, the forward portion of the bag mouth extending loosely and freely between the ends of the arms 26 and 27. The spring arm 31 is then forced inwardly against its spring tension and the depending portion 37 inserted in the bag mouth against the front edge thereof. 40 When the arm 31 is released the bag mouth is forced outwardly and downwardly by the spring coil 32 into a V-shaped stretched position as indicated in the drawings. This allows of holding the bag mouth in such a 45 position as to allow of the easy pouring in of the contents of the bag through the mouth.

If it is desired to shake the contents of the bag down all that it is necessary to do is to 50 grip the arms 26 and 27 and lift the bag up completely so that the hook portions 23 of the arms 21 and 22 are lifted off the arms of the bar 18. The bag may then be shaken down and replaced when desired.

55 If it is found necessary to fill the bag in a barn where the floor is covered with grain or the floor is otherwise uneven and unadaptable for placing a stand having a substantially flat bottom thereon or if it is 60 necessary to fill the bag out in the field where the ground is uneven the standard 12 may be removed by withdrawing the split pin 15 and raising the standard vertically from the orifice 11 and through the bracket

10. The hooked upper end of the stem may 65 then be placed over a suitable support such as shown at 47 (see Fig. 3) or in the case where the bag is being filled in the field it may be placed over the edge of the wagon box.

70 In order to adjust the device for different heights of bags all that it is necessary to do is to loosen the set screw 20 and raise or lower the bag 18 to the desired position and retighten the set screw 20. If it is necessary to remove the bag after being filled the truck support may be tilted to the horizontal position, the mouth of the bag closed and the bag removed to any desired location.

75 In some cases it is desirable to use a certain class of bags which have very much larger mouths than are ordinarily used and which are too large to be stretched tightly by the ordinary bag stretching means. In order to overcome this defect I have provided a tightener. When this is employed the mouth of the bag is folded over the bag mouth stretcher in the usual way and the edge of the over-folded portion inserted in the split of the pin 41. The pin is then 80 turned by means of the flattened end 43 so as to wind the fabric of the bag around the pin, the pin being held in such position by the ratchet dog 46 co-acting with the ratchet 45. By this means all slack in the mouth of 85 the bag is taken up and the bag stretched tight around the stretching frame.

90 From this description it will be seen that I have devised a very simple form of bag holder which may be either used as a standard holder having an integral base, which base may be used as a truck for transporting the filled bag from place to place, or may be used in locations unsuitable for supporting the base over the standard in which 95 case the standard may be hung on a suitable support during the process of filling, and in which the frame of the mouth spreader of the bag may be used as a frame whereby the bag may be lifted manually from the holder, 100 shaken down and replaced without disturbing the bag mouth.

105 110 115 What I claim as my invention is:

1. In a device of the class described, a bag mouth stretcher comprising a bar having forwardly and outwardly inclined ends and around the upper edge of which the rear portion of the bag mouth is folded, and a spring finger carried by one of the aforesaid inclined arms and having a down-turned 120 outer end designed to be sprung rearwardly into position within the bag mouth.

125 120 125 2. In a device of the class described, a bag mouth stretcher comprising a bar having forwardly and outwardly inclined ends around the upper edge of which the rear portion of the bag mouth is folded, resilient means for stretching the forward portion of the

bag mouth, and means for taking up any superfluous slack in the bag mouth and comprising a right angled bracket having a turned over upper end supported upon one of the inclined arms, a split pin journaled therein into the split of which the bag edge is designed to be inserted, means for turning

the pin, and means for holding the pin in any position to which it is turned.

WILLIAM WATSON CAMP.
